P. HAUSMEISTER

SAFETY DEVICE FOR GAS-FILLED SPACES

Filed July 27, 1925.

Inventor:
Paul Hausmeister
by Kneidler
Atty.

UNITED STATES PATENT OFFICE.

PAUL HAUSMEISTER, OF GOPPINGEN, GERMANY.

SAFETY DEVICE FOR GAS-FILLED SPACES.

Application filed July 27, 1925. Serial No. 46,301.

To all whom it may concern:

Be it known that I, PAUL HAUSMEISTER, a citizen of Germany, residing at Goppingen, Germany, have invented certain new and 5 useful improvements in Safety Devices for Gas-Filled Spaces, of which the following is a specification.

My invention relates to safety devices for gas filled spaces. It is an object of my invention to provide means for preventing the 10 spreading of an explosion occurring in spaces communicating with the space protected by the new device. Safety devices have been proposed comprising a plug of porous material traversed by the gas, the operation of such devices being based on the Davy principle and being further due to the fact that the gas flows in the passages of the porous material at a velocity which is higher than 15 the velocity of propagation of the explosion. However, devices of this kind do not afford absolute protection inasmuch as it may occur that the flame continues burning at the discharge surface of the porous material and 20 thereby heats the material so as to cause the gas mixture to be ignited at the rear of the safety device.

It is an object of my invention to overcome this drawback by providing a body of 25 liquid such as water on the discharge side of the porous plug which prevents the flame of the explosion from coming in contact with the plug.

In the drawings affixed to this specification 30 and forming part thereof, the application of my invention to an electrolyzer is illustrated diagrammatically in vertical section by way of example.

Referring to the drawings *c* is a high- 35 pressure electrolyzer tank in which oxy-hydrogen gas is generated at the electrodes *a* and *b* and collected in the chamber *d* at the top of the tank *c*.

A second tank *h* is arranged above the 40 tank *c* and connected therewith by a narrow neck *k* in which is inserted a plug *e* of

porous material. The second tank is filled with water *f* above the plug *e* so that the gas from the chamber *d* can rise in small bubbles and can collect in the top *g* of tank *h* ending in a discharge pipe *i*. The porous plug *e* prevents water from dripping into the chamber *d*. 50

If an explosion is propagated into the collecting chamber *g*, which is preferably small, 55 backward ignition to the chamber *d* is prevented as an uninterrupted flow of gas through the body of water is impossible.

It is not necessary that the plug *e* should consist of a single solid body. It might also 60 be composed of granular or pulverulent material suitably packed. Preferably a porous solid body at the bottom is combined with a layer of loose pulverulent material arranged above it. With this arrangement cracks 65 which may form in the solid body are harmless.

Obviously any liquid other than water might be disposed above the porous plug *e*.

I wish it to be understood that I do not 70 desire to be limited to the exact details of construction shown and described, for obvious modifications will occur to a person skilled in the art.

I claim:

1. Safety device for gas filled spaces comprising a porous partition arranged in the path of the flowing gas, and a liquid column above said partition.

2. Safety device for gas filled spaces comprising a porous body and pulverulent material combined to form a partition arranged in the path of the flowing gas, and a liquid column above said partition. 80

3. Safety device for electrolyzers comprising an electrolytic cell, a liquid filled container on top of said cell, a narrow neck connecting said container and said cell, and a porous partition in said neck. 85

In testimony whereof I affix my signature.

PAUL HAUSMEISTER.
